UNITED STATES PATENT OFFICE.

DAVID DARNLEY, OF LONACONING, MARYLAND.

RAILWAY-SWITCH.

1,044,147.

Specification of Letters Patent. Patented Nov. 12, 1912.

Application filed November 15, 1911. Serial No. 660,355.

To all whom it may concern:

Be it known that I, DAVID DARNLEY, a citizen of the United States, residing at Lonaconing, in the county of Allegany and State of Maryland, have invented certain new and useful Improvements in Railway-Switches, of which the following is a specification, reference being had to the accompanying drawings.

This invention is an improved railway switch wherein the outer rails of the main and side tracks are continuous at the point of intersection of said tracks and wherein the switch rails are connected together and pivotally mounted for simultaneous angular movement, to open or close the switch and avoid the use of frogs, and hence preventing accidents such as are caused by the use of frogs in switches, the invention consisting in the construction, combination and arrangement of devices hereinafter described and claimed.

In the accompanying drawings: Figure 1 is a plan of a railway switch constructed in accordance with my invention; Fig. 2 is a transverse sectional view of the same on the plane indicated by the line *a—a* of Fig. 1; and Fig. 3 is a similar view on the plane indicated by the line *b—b* of Fig. 1.

For the purposes of this specification the main track is indicated at 1 and the side track at 2. The opposite or outer rails of the main and side tracks are, in accordance with my invention, continuous at the point of intersection of the said tracks, the outer main track 2 being straight and the outer side track, which also forms a portion of the main track, being indicated at 3, and having straight end portions 4, 5 which respectively align with the main and side tracks and an intermediate curved portion 6, the chord of which is at an angle to the main track. The converging ends of the inner rails 7, 8 of the main and side tracks are slightly spaced apart and are secured on a plate 9. This plate is secured on a main plate 10 which is secured on certain of the ties. The plate 9 has a curved stop flange 11 formed integral therewith, projecting from the upper side thereof and extending across the ends of the bases of the rails 7, 8. The said plate is also provided on its upper side with stops 12, 13. The plate 14 is secured on certain of the ties and extends under the rail 2 and the rail 3 at the angle

15 of the latter, and at a point intermediate the ends of the switch is a similar plate 16. I also provide a pair of shiftable switch rails 17, 18. These switch rails are disposed in converging relation toward the 60 ends of the rails 7, 8 and have their converging ends, which are slightly spaced apart, connected by a bar 19. The opposite ends of the switch rails are split. That is to say, they are beveled on their outer sides 65 as at 20, 21, respectively, and the said split ends of the switch rails are also connected together by a bar 22. The switch rails are also connected together by an intermediate bar 23. The switch rail 18 is straight so as to exactly align with the main track when the switch is closed, and the switch rail 17 is slightly curved so as to exactly align with the curved portion 6 of the continuous rail 3 when the switch is open. The switch rails 75 17, 18 are also connected together intermediate of their ends by a plate 24 which is pivotally mounted on a base plate 25 that is secured on one of the cross ties. The base plate has a cylindrical boss 26 on its upper side provided in its upper end with an annular groove 27 and the plate 24 has a similar boss 28 on its lower side provided with an annular flange 29 which operates in the groove 27. The plate 24 is also connected 80 to the base plate by a pivot bolt 30. Hence the switch rails, which are connected together for simultaneous movement, are pivotally mounted at a point intermediate their ends. When the switch rails are in the position shown in Fig. 1 the rail 18 aligns with the main track and its split end bears snugly against the inner side of the continuous rail 3 and, hence, the main track is entirely unobstructed at the switch, there is no frog at the switch and no danger of derailing a passing train. When the switch rails are moved to open position the rail 17 aligns with the curved portion of the continuous rail 3 and its split end 20 bears 85 against the inner side of the outer rail of the main track and the split end 21 of the switch rail 18 is disposed at a distance from the continuous rail 3 and hence the side track is open and a train encounters no obstruction either in entering or leaving the side track through the switch. I also provide stops 31, 32 on one of the cross ties 90 for the switch rails 17, 18, respectively, and, in practice, the switch rails are operated 105 110

by the usual switch lever through the instrumentality of the usual rod indicated at 33.

It will be noted that whichever way the switch is thrown it will form a butt joint at the frog end and a split joint at the opposite end. Since the switch rails are firmly connected together it is impossible to move one without the other. Moreover, by 10 having the outer rails continuous on the main and side tracks at the point of intersection the switch is rendered exceedingly strong and the train wheels encounter no obstructions in passing the switch and, 15 hence, there is no likelihood of an accident.

Having thus described my invention I claim:

A railway switch, embodying fixed continuous outer main and siding rails, converging inner main and siding rails terminating at one end in laterally spaced relation to each other, and switch rails mounted between the continuous outer main and

siding rails and secured together for a laterally swinging movement, the said switch rails converging in the direction of the converging inner main and siding rails and in slightly spaced relation thereto, and a plate disposed underneath the adjoining ends of the switch rails and said converging inner 30 main and siding rails and formed with a curved stop flange interposed between the adjoining ends of the switch rails and the corresponding ends of the main and siding inner rails and abutting against all of said 35 adjoining ends and of a length to bear against the adjoining ends of the switch rails throughout the arc of movement of the latter.

In testimony whereof I hereunto affix my 40 signature in the presence of two witnesses.

DAVID DARNLEY.
